INVENTOR

BY *Victor J. Evans*

ATTORNEY

W. L. Lamm

WITNESS:

UNITED STATES PATENT OFFICE.

EDWARD L. AIKEN, OF EAST ORANGE, NEW JERSEY.

COMBINED JACK AND SWITCH.

Application filed February 21, 1924. Serial No. 694,343.

To all whom it may concern:

Be it known that I, EDWARD L. AIKEN, a citizen of the United States, residing at East Orange, in the county of Essex and State 5 of New Jersey, have invented new and useful Improvements in Combined Jacks and Switches, of which the following is a specification.

This invention relates to electrical contact 10 or control devices and has for its object the provision of a novel combined jack and switch designed primarily for use in connection with radio apparatus.

An important object is the provision of a 15 device of this character usable simply as a switch and also capable of employment as a single or multiple circuit jack, the device being adapted for mounting upon an ordinary panel and being of such a nature as to 20 operate with the ordinary and well known type of phone plug.

Another object is the provision of a device of this character which is not only compact but which will also have minimum 25 electrical capacitance, a feature of the utmost consideration when used in radio apparatus.

An additional object is the provision of a 30 device of this nature which will be simple and inexpensive to manufacture, easy to install, positive in action, efficient and durable in service and a general improvement in the art.

With the above and other objects and advantages in view the invention consists in the details of construction to be hereinafter more fully described and claimed and illustrated in the accompanying drawings, in which:

40 Figure 1 is a plan view of one form of the device.

Figure 2 is an elevation at right angles to Figure 1.

Figure 3 is a cross section,

45 Figure 4 is a longitudinal section showing a solid plug inserted within the device,

Figure 5 is a view similar to Figure 4 showing a telephone plug inserted within the device,

50 Figure 6 is a detail view of a modified or single contact form.

Referring more particularly to the drawings the numeral 10 designates the body formed of suitable insulating material such

as bakelite, hard rubber, fiber or the like and 55 of any desired size and shape. In the present instance this block or body is illustrated as rectangular. This body is formed with a cylindrical hole 11. At one side the body is formed with spaced parallel grooves 12 60 which intersect the hole 11. The body is mounted by a screw S, on an L-shaped bracket 13 which has one arm formed with a threaded hole 14 leading into the hole 11. For mounting the device upon a panel or 65 the like, I provide a thimble 15 having a threaded end screwed into the hole 14 and having its opposite end formed with a head 16. The thimble 15 passes through the panel 70 A, the bracket 13 bearing against the rear side of the panel and the head 16 bearing against the front thereof. The thimble is formed with a hole 17 registering with the hole 11 in the body.

Secured upon one side adjacent that one 75 having the grooves 12 therein, are metallic contact strips 18 and 19 which are similar and which terminate in lateral extensions 20 and 21. These contact strips are held in place by screws 22 and 23 respectively which 80 also act as binding means for wires of the circuit in which the device is used.

Disposed at the opposite side of the body are angular metallic contact strips 24 and 25 held in place by screws 26 and 27 respectively which may additionally serve as binding means for wires, altho it is preferable to connect the wires by soldering them to the ends 32 of the contact strips 24 and 25 which may be straight or bent as indicated in the drawing. The contacts 24 and 25 include arms 28 and 29 respectively which lie within the grooves 12 and which normally engage against the respective extensions 20 and 21 of the contacts 18 and 19.

When the device is used as a simple switch, wires are connected with the contacts 24 and 25 either by soldering the wires to the ends 32 or by connecting them under the head of the screws 26 and 27. For completing the circuit through these wires, use is made of a plain metallic plug 30 which is inserted through the registering holes 17 and 11. When such a plug is inserted, it 95 will engage against the contact arms 28 and 29 and bridge them. When the plug is removed the circuit is broken in an obvious manner. If desired connection might be 100 105

made to the contacts 24 and 18 or 25 and 19. In this instance the circuit would be broken upon the insertion of the plug.

For employing the device as a single closed circuit jack, use is made of a standard jack plug B, which as is well known, includes a metallic shank C and a tip D insulated therefrom, both having respective terminals. The contacts 18 and 19 are replaced by a single contact 31 of a size to be engaged by both 28 and 29. The wires in the circuit are connected with the contacts 24 and 25 and it will be apparent that when the plug is in place, the shank thereof will engage the contact 24 while the tip will engage the contact 25. When the plug is removed the circuit therethrough is broken and current passes through members 24 and 25 and contact 31. It is obvious that by leaving off plate 31 and contacts 18 and 19 the jack would then serve the purpose of controlling a single open circuit.

The device is also capable of performing the functions of a double closed circuit jack and in this instance the same standard jack plug is used, the wires in the two circuits being connected with the contacts 24 and 25, and 18 and 19. When the plug is inserted, the arms 28 and 29 engaged thereby will be moved out of engagement with the extensions 20 and 21 of the contacts 18 and 19 and the circuit will be through the contacts 24 and 25, the plug tip and its shank. When the plug is withdrawn, the natural resilience of the arms 28 and 29 will cause them to re-engage the extensions 20 and 21, thus completing the circuits directly through the contacts 24 and 18 and 25 and 19.

From the foregoing description and a study of the drawings it will be apparent that I have thus provided a simple, neat, inexpensive and easily connected and operated jack capable of use in several different combinations depending upon the nature of the circuits to be controlled.

While I have shown and described the preferred embodiment of my invention it is of course to be understood that I reserve the right to make such changes in the form, construction and arrangement of parts as will not depart from the spirit of the invention or the scope of the subjoined claims.

I claim:

1. A device of the character described comprising a body of insulating material having a hole therethrough and provided with grooves intersecting the hole, angular contacts secured upon one side of the body and having arms lying within said grooves in obstructing relation to the hole, a plurality of contacts secured upon the opposite side of the body and normally engaged by said arms, in combination with a plug insertable throughout the hole for engagement with said arms.

2. A device of the character described comprising a body of insulating material having a hole therethrough and provided with grooves intersecting the hole, angular contacts secured upon one side of the body and having arms lying within said grooves in obstructing relation to the hole, a plurality of contacts secured upon the opposite side of the body and normally engaged by said arms, in combination with a plug insertable throughout the hole for engagement with said arms, a support for said body, one end of the support having a threaded opening leading into said hole, and a thimble screwed into said threaded opening in the support and disposable through a mounting, the thimble terminating in a head.

3. A device of the character described comprising a body of insulating material having a hole therethrough, a support for the body, a mounting thimble screwed into one end of the support and having a hole registering with said first named hole, the body being formed in one side with spaced parallel grooves intersecting the first named hole, a plurality of contacts secured upon one side of the body and having angular extensions, and a plurality of angular contacts secured upon the opposite side of the body and including arms lying within said grooves in obstructing relation to the first named hole and normally contacting said extensions, in combination with a plug insertable through the registering holes for engagement with said arms.

4. A device of the character described comprising a body of insulating material having a hole therethrough, a support for the body, a mounting thimble screwed into one end of the support and having a hole registering with said first named hole, the body being formed in one side with spaced parallel grooves intersecting the first named hole, a pair of contacts secured upon one side of the body and having angular extensions, and a pair of angular contacts secured upon the opposite side of the body and including arms lying within said grooves in obstructing relation to the first named hole and normally contacting said extensions, in combination with a plug insertable through the registering holes for engagement with said arms, the respective contacts being adapted for connection in different types of circuits whereby the device is operable as a switch, single circuit jack or multiple circuit jack.

5. A device of the character described comprising a body of insulating material having a hole therethrough and provided with at least one transverse groove intersecting the hole, at least one contact secured to the body and having an arm formed to substantially the transverse contour of the body and lying in said transverse groove

intersecting said hole, and at least one contact secured to the body and normally in engagement with said arm, said hole being adapted to receive a member for engagement with said arm.

6. A device of the character described comprising a body of insulating material having a hole therethrough and provided with at least one transverse groove intersecting the hole, and at least one contact secured to one side of the body and having an arm bent over another side of the body and lying in said transverse groove intersecting said hole, said hole being adapted to receive a member capable of longitudinal movement therein to engage and disengage with said arm.

7. A device of the character described comprising a body of insulating material having a hole therethrough and provided with a plurality of spaced transverse grooves intersecting the hole, a plurality of angular contacts secured to the body and each having an arm bent to substantially conform to the transverse contour of the body and lying in its respective groove and intersecting said hole, and a plurality of contacts secured to the body and normally in engagement with said arms, said hole being adapted to receive a member capable of longitudinal movement therein to engage and disengage with said arms.

8. A device of the character described comprising a body of insulating material having a hole therethrough and provided with a plurality of grooves on one side of the body and intersecting said hole, angular spring contacts fastened to an adjacent side of the body and having arms lying in said

grooves across said hole, and contacts secured on opposite sides of the body and normally in engagement with said arms, said hole adapted to receive a slidable member for engaging said arms.

9. A device of the character described comprising a body of insulating material having a hole therethrough and provided with a plurality of grooves on one side of the body and intersecting said hole, angular spring contacts fastened to an adjacent side of the body and having arms lying in said grooves across said hole, and at least one member secured to an opposite side of the body and normally in engagement with at least one of said arms, said hole adapted to receive a slidable member for engaging said arms.

10. A device of the class described comprising a body of insulating material having a hole therein and provided with at least one transverse groove intersecting said hole and at least one contact secured to one side of the body and having an arm bent over another side of the body and lying in said transverse groove intersecting said hole, said hole being adapted to receive a member for engagement with said arm.

11. A device of the character described comprising; a body of insulating material having a single longitudinal opening therethrough, at least one transverse contact member attached to an outer surface of said insulating material projecting across said opening, said opening adapted to receive a slidable member for engaging said contact member.

In testimony whereof I affix my signature.
EDWARD L. AIKEN.
